FOUNDATION GARMENT

Frances Sider, New York, N. Y.

Application October 4, 1951, Serial No. 249,745

4 Claims. (Cl. 2—30)

1
This invention relates to a combined brassière and girdle or panty girdle foundation.

Broadly, it is an object of the invention to provide a combination brassière and foundation garment in which the brassière is connected at its lower front portion to the upper front portion of the foundation garment and the back portions of the respective portions are open, or not connected.

More particularly, it is an object of the invention to provide the lower front portion of the brassière with separable fastener means so that the brassière may be detached from or attached to the front upper part of the girdle, or panty girdle, as desired.

Another object of the invention is to provide spirals behind the tapes of the separable fasteners of the girdle, or panty girdle, and longer spirals and a short central spiral at the upper rear part of the girdle, or panty girdle, to provide proper support and prevent the girdle, or panty girdle, from "bunching up" at the rear waistline when straightening up from a bending position.

For a fuller understanding of the nature and objects of the invention, reference is had to the following detailed description in connection with the accompanying drawings, in which:

Fig. 1 is a rear view of the combination brassière and panty girdle showing the brassière disconnected at the rear;

Fig. 2 is a front view thereof;

Fig. 3 is an enlarged detailed view showing one of the spirals;

Fig. 4 is a perspective view from the front of the combination brassière and panty girdle upon the person;

Fig. 5 is a perspective view from the rear of the combination brassière and panty girdle upon the person; and

Fig. 6 is a perspective view from the front of the combination brassière and girdle.

Referring to the drawings, numeral 10 represents a combination brassière and panty girdle. While I have shown a panty girdle in the drawings, it is to be understood that a girdle may be used in place of the panty girdle shown. This garment comprises a brassière 11 and a panty girdle 12. The brassière comprises a pair of breast pockets 13, 13 and lower front portions 14, 14 which are between the breast pockets and the waistline. Behind each of the lower front portions is a reinforcing panel 38, as shown in Fig. 1, which runs from beneath the breast pocket to the waistline, the fabric being set on the bias to enable the wearer to breathe without

restriction and to aid in molding the diaphragm. Between the breast pockets 13, 13 and the lower front portions 14, 14 there is a vertical central panel 15 divided by a median fagoted line 16 running from the upper part to the lower part of the brassière. The lower portion of the breast pockets 13, 13 and the lower front portions 14, 14 are also centrally divided, as shown at 17, 17. Side panels 18, 18 are attached to the outer sides of the breast pockets 13 and the lower front portions 14 which in turn are attached to encircling elastic back bands 19, 19 which are stretchable horizontally, as indicated by the arrow. The outer ends of the elastic back bands 19 have a vertical series of hooks and eyes designated as 20 and 21, respectively, as is well known in the art. The rear front lower end of the lower front portions 14, 14 and the vertical central panel 15 have stitched thereto a non-stretchable band of female snap fasteners 22 for the purpose hereinafter described. Behind the vertical ends of the lower front portions and the arcuate outer ends of the breast pockets are narrow pockets 23, 23 and 24, 24 for housing spirals 25, as shown in Fig. 3. Vertical pockets 26, for housing other spirals, are also stitched behind the outer ends of the side panels 18 and the inner ends of the elastic back bands 19. The spirals 25, which are preferably made of stainless flexible steel and are well known in the art, run the full height of the brassière at the portions designated, that is, between the waistline and the top of the brassière and curve around the breast pockets, as indicated best in Fig. 2, to avoid undue pressure upon the breasts and maintain the brassière 11 in upright position upon the wearer without the use of shoulder straps.

The panty girdle 12, shown in the drawings, is comprised completely of elastic panels, to wit, a front central panel 27 cut somewhat on the bias so that it is stretchable diagonally to stretch with the ligaments of the abdomen, thus controlling the abdomen without restriction, a pair of opposed front panels 28, 28, one on either side of the central panel 27 and stretchable horizontally. The back of the panty girdle 12 comprises a rear central panel 29 stretchable vertically and opposed rear panels stretchable horizontally. The outer ends of the front and side panels 28 and 30, respectively are joined by stitching except for a portion running from the top of the panty girdle to somewhat below the center thereof which has two opposed separable fasteners 31, 31 to permit the garment 55 to be taken off and placed upon the wearer with

greater ease and facility. When both separable fasteners 31, 31 are opened or separated, the seat automatically drops so that the entire girdle need not be removed when the wearer goes to the bathroom. Adjacent one side of each of the separable fasteners 31, 31, and preferably toward the inside thereof, there is a pocket containing a spiral 32 running approximately the full length of the separable fasteners 31, 31. Approximately at the point where the rear central panel 29 is attached to the opposed rear panels 30, 30 there is also a pair of opposed pockets and spirals 33, 33 running from the top of the back of the girdle to somewhat slightly below the center of the rear panel 29. Also, in the upper central portion of the rear central panel 29 there is a short vertical pocket containing spiral 34 which prevents the girdle, or panty girdle, from "bunching up" at the rear waistline when the wearer bends down and then straightens up from the bending position. In the panty girdle, between the lower portion of the front panels 28 and rear panels 30, there is a stretchable crotch member 35 stretchable in the direction shown by the arrow in Fig. 1. A removable auxiliary crotch member is removably fastened at the inside of the crotch member 35 so that it may be washed whenever desired. Along the inside of the upper front portion of the panty girdle 12 there is a non-stretchable tape 36 containing a series of uniformly spaced male snap fasteners to coat with the female snap fasteners 22 for detachably joining the brassière 11 to the girdle 12 so that both the brassière and the girdle can be worn independently of each other, if desired, or in the combined form, as shown in Figs. 1 and 2. When the brassière and girdle are attached, a smooth front results and the closing is completely concealed. It is to be understood that if desired the bottom of the brassière 11 and the top of the girdle 12 may be stitched together permanently but in either event, that is, whether or not the garment is made detachable or is permanently stitched together, the rear portion of both the top of the girdle and the bottom of the brassière are not connected so that there is an open space therebetween which will permit the wearer to bend forward and straighten herself, causing the rear bottom of the brassière and the top rear edge of the girdle to move apart and move toward each other during such bending and straightening movements. The lower leg portions of the girdle have attached thereto the well known hose supporters 37.

It is obvious that various changes and modifications may be made in the details of construction and arrangement of parts without departing from the general spirit of the invention.

I claim:

1. In a foundation garment, the combination of a brassière and a girdle, the lower front edge

of the brassière being secured to the upper front edge of the girdle, the lower rear edge of the brassière being free with respect to the upper rear edge of the girdle, said brassière comprising front panels having breast pockets, side panels and back bands, the free ends of the back bands being detachably connected together, resilient spirals extending along the side edge portions of the front panels and around the outer side edges of the breast pockets, said girdle comprising a front central panel that extends downwardly from the upper front edge of the girdle, opposed front panels connected to the respective side edges of the front central panel, a rear central panel extending downwardly from the upper rear edge of the girdle, opposed rear panels connected at their inner side edges to the respective side edges of the rear central panel, the outer side edges of the opposed front panels being connected to the outer side edges of the respective opposed rear panels along the lower side edge portions thereof, the upper outer side edge portions of the front and rear panels at each side of the girdle being open, coacting separable fastening means extending along the open outer side edges of said panels, said opposed front panels being formed with pockets that extend adjacent the separable fastening means, and resilient spirals arranged in said pockets.

2. A structure of the character recited in claim 1, wherein the front panels of the brassière below the breast pockets are stretchable.

3. A structure of the character recited in claim 1, wherein the front central panel of the girdle is stretchable diagonally and the rear central panel is stretchable vertically and the front and rear opposed panels are stretchable horizontally.

4. A structure of the character recited in claim 1, wherein the lower front edge of the brassière is detachably connected to the upper front edge of the girdle.
